United States Patent

Des. 240,765

Patented July 27, 1976

240,765

HOLDER FOR MICROFICHE CARRIERS

Clyde E. LeFevre, Orange, Gregory A. Leland, Huntington Beach, and William R. Swift, Placentia, Calif., assignees to Addressograph-Multigraph Corporation, Cleveland, Ohio

Filed Feb. 6, 1975, Ser. No. 547,631

Term of patent 14 years

Int. Cl. D16—05

U.S. Cl. D16—26

Fig. 1

Fig. 2

FIG. 1 is a top perspective view of a holder for microfiche carriers showing our new design;

FIG. 2 is a top plan view thereof;

FIG. 3 is a front elevational view thereof;

FIG. 4 is a right-side elevational view thereof; and

FIG. 5 is a left-side elevational view thereof.

The undisclosed bottom of the design is plain and unornamented.

We claim:

The ornamental design for a holder for microfiche carriers, substantially shown and described.
